(57) CLAIM

The ornamental design for a shelf front, as shown and described.

DESCRIPTION

FIG. 1 is a perspective view of a shelf front showing my new design;

FIG. 2 is a top elevational view thereof;

FIG. 3 is a front elevational view thereof;

FIG. 4 is a back elevational view thereof;

FIG. 5 is a right side elevational view thereof, the left side elevational view being a mirror image of the right side; and, FIG. 6 is bottom elevational view thereof.

The broken line showing is for illustrative purposes only and forms no part of the claimed design.
